UNITED STATES PATENT OFFICE

171,734

TABLE LAMP

Rudolph Scheynost, Chicago, Ill.

Application April 17, 1953, Serial No. 24,545

Term of patent 14 years

(Cl. D48—20)

To all whom it may concern:

Be it known that I, Rudolph Scheynost, a citizen of the United States and residing in the city of Chicago, in the county of Cook and State of Illinois, have invented a new, original, and ornamental Design for a Table Lamp, of which the following is the specification, reference being had to the accompanying drawings, forming a part thereof,

On the drawings:

Fig. 1 is a top plan view of a table lamp, showing my new design; and

Fig. 2 is a perspective view thereof.

The dominant features of my design are shown in solid lines.

I claim:

The ornamental design for a table lamp, substantially as shown and described.

RUDOLPH SCHEYNST.
